DOG BOOT

James W. Jackson, 1526A Mews Drive,
Kansas City, Mo. 64131

Filed Mar. 6, 1970, Ser. No. 21,770

Term of patent 14 years

Int. Cl. D30—01

U.S. Cl. D30—34

Fig. 1.

Fig. 2.

Fig. 3.

Fig. 4.

Fig. 5.

Fig. 6.

Fig. 7.

FIG. 1 is a top plan view of a dog boot showing my new design;

FIG. 2 is a front elevational view thereof;

FIG. 3 is an end elevational view thereof;

FIG. 4 is a side elevational view showing the dog boot in condition ready for mounting upon the paw of a dog;

FIG. 5 is a side elevational view showing the dog boot as mounted;

FIG. 6 is a front elevational view showing the dog boot as mounted; and

FIG. 7 is a rear elevational view showing the dog boot as mounted.

I claim:

The ornamental design for a dog boot, as shown and described.
